Primary Examiner — Khawaja Anwar*Assistant Examiner* — Julice Seung Eun Oum(74) Attorney, Agent, or Firm — McAndrews Held & Malloy, Ltd.(57) CLAIM

The ornamental design for a gaming machine, as shown and described.

DESCRIPTION

FIG. 1 is a front perspective view of a gaming machine showing our new design;

FIG. 2 is a front elevation view thereof;

FIG. 3 is a rear elevation view thereof; and,

FIG. 4 is a top plan view thereof.

The dashed broken lines in the figures illustrate portions of the gaming machine that form no part of the claimed design.

1 Claim, 4 Drawing Sheets(56)
